United States Patent Office

Des. 183,435

Patented Aug. 26, 1958

183,435

ELECTRONIC CABINET

James G. Wells, Chicago, and Herbert C. Golz, Aurora, Ill., assignors to Elgin Metalformers Corporation, Elgin, Ill., a corporation of Illinois

Application September 24, 1957, Serial No. 47,841

Term of patent 14 years

(Cl. D26—5)

Fig. 1 is a perspective view of an electronic cabinet showing our new design;

Fig. 2 is a front elevational view;

Fig. 3 is a rear elevational view; and

Fig. 4 is a top plan view thereof.

We claim:

The ornamental design for an electronic cabinet, substantially as shown.
